UNITED STATES PATENT OFFICE

118,421

DESIGN FOR A KITCHEN VENTILATOR

Bernhard Sonntag, Dallas, Tex.

Application June 30, 1939, Serial No. 85,784

Term of patent 7 years

To all whom it may concern:

Be it known that I, Bernhard Sonntag, a citizen of the United States, residing at Dallas, in the county of Dallas and State of Texas, have invented a new, original, and ornamental Design for Kitchen Ventilators, of which the following is a specification, reference being had to the accompanying drawing, forming part thereof.

I claim:

The ornamental design for a kitchen ventilator, substantially as shown and described.

BERNHARD SONNTAG.
